UNITED STATES PATENT OFFICE

LEON FRANK, OF BALTIMORE, MARYLAND, ASSIGNOR TO ALMA MANUFACTURING COMPANY OF BALTIMORE CITY, OF BALTIMORE, MARYLAND, A CORPORATION OF MARYLAND

DESIGN FOR AN APPAREL BUCKLE

Application filed June 5, 1930. Serial No. 35,934. Term of patent 3½ years.

To all whom it may concern:

Be it known that I, LEON FRANK, a citizen of the United States, residing at Baltimore, in the State of Maryland, have invented a certain new, original, and ornamental Design for Apparel Buckles, of which the following is a specification, reference being had to the accompanying drawing, forming part thereof.

I claim:

The ornamental design for an apparel buckle, as shown.

In testimony whereof I have hereunto set my hand this 3rd day of June, A. D. 1930.

LEON FRANK.
